Primary Examiner — S. Bryan Reinholdt, Jr.

(57) **CLAIM**

The ornamental design for an electronic cigarette, as shown and described.

DESCRIPTION

1. Electronic cigarette

1.1 : Perspective

1.2 : Front

1.3 : Back

1.4 : Left

1.5 : Right

1.6 : Top

1.7 : Bottom

The present design relates to an electronic cigarette; The electronic cigarette is of a flat sheet-like structure, and all side edges of the electronic cigarette are rounded, where a front end of the electronic cigarette is a semi-elliptical mouthpiece having a thickness decreasing toward the front end, and a rear end of the electronic cigarette is a charging portion having an approximate semi-circular structure.
